COMBINED PRESSURE AND CENTRIFUGAL EXTRACTOR

George W. Johnson, Cincinnati, Ohio, assignor to The American Laundry Machinery Company, Cincinnati, Ohio, a corporation of Ohio

Application June 12, 1931. Serial No. 543,829

9 Claims. (Cl. 210—63)

My invention relates to a centrifugal extractor and, particularly, to a centrifugal extractor including mechanical means for expelling liquid from material by a squeezing action other than that brought about centrifugally, in conjunction with a means for extracting liquid therefrom by centrifugal action.

The invention as hereinafter described is particularly adapted for use in laundries as a means 10 for removing liquid from fabric although it may be adapted to many other uses and industries. In laundries, centrifugal action is effective to remove liquid from fabric in a length of time and to a degree proportional to the speed of rotation of 15 the extractor basket. Therefore, it has heretofore been necessary to rotate the extractor basket at a high rate of speed for a predetermined time in order to remove the excess liquid from the fabric, leaving in the material only enough liquid to give 20 the material sufficient dampness for proper ironing.

My invention contemplates the provision of a mechanical pressure applying means other than centrifugal force that follows the load, positioned by the centrifugal action so that a force 25 necessary to expel liquid from the material is exerted on the material along substantially the lines of flow of the fluid due to centrifugal action, in conjunction with the usual centrifugal extracting 30 means, whereby the fabric may be subjected to mechanically applied pressure and centrifugal force along substantially the same lines to force the water out of the fabric by squeezing action. This mechanical pressure applying means is of a 35 nature to be used either in unison or successively with the centrifugal extracting operation and provides a means for reducing the time necessary to sufficiently remove the liquid from the fabric, for removing the liquid under less dangerous conditions than usual, and for making removal of 40 the liquid from the fabric in a given time possible with a substantially slower speed of rotation of the basket than has heretofore been possible. Thus a relatively great saving is acquired in the 45 power necessary to rotate the basket. Likewise, the time necessary for completing extraction being materially shortened, more goods can be treated in a given space of time. A saving will also be had in the cost of building the extractors due to 50 the fact that the slow speed necessary of the extractor basket will not require a design of a type to withstand the enormous centrifugal forces of a basket rotating at a high rate of speed.

Various objects and advantageous features of 55 my invention will be apparent from the following

description and one embodiment thereof may be seen in the accompanying drawing wherein similar characters of reference designate corresponding parts, and wherein the figure is a vertical section of a centrifugal extractor including a mechanical pressure applying means other than the usual centrifugal action constructed in accordance with my invention.

Referring to the drawing, I have shown a centrifugal extractor mechanism consisting of a curb or casing 1 provided with a hinged cover 2 adapted to close the open top thereof and a bottom 3 having an extension 4 on which a motor or power unit 5 for rotating a perforated basket 6 is mounted and suitable spaced supporting lugs 7 connected by links 8 to upright standards 9 spaced about a supporting frame or base 10. Such mounting of the curb or casing 1, motor or power unit 5, and basket 6, as well as all interconnected operating parts, permits vibratory and oscillatory movement of the apparatus brought about by rotation of the basket 6 without the usual destructive action on the apparatus.

The curb or casing bottom 3 is provided at its center with a suitable bearing 11 in which a vertical shaft 12 is arranged to rotate, the shaft 12 carrying a belt pulley 13 at its lowermost end which is connected to a motor or power unit pulley 14 by means of a belt 15. A conical shaped bottom 16 of the perforated basket 6 is secured to the upper end of the shaft 12 whereby the goods container 6 will be rotated when the motor or power unit 5 is operating. As shown, a removable cover 17 is provided to close the upper open end of the basket 6 and has means such as sliding bolts 18 that cooperate with the vertical walls of the basket 6 for locking the cover in place.

In accordance with my invention, a means for applying mechanical pressure to fabric within the rotatable basket 6 is provided that takes the form of a suitably shaped bag 19 of rubber or other air-tight material attached to the central portion of the basket cover 17 as at 20 and to the upper end of the shaft 9 in such manner that the interior of the bag 19 is in communication with a central bore 21 in the shaft 9. It will be understood that there may be a plurality of the bags 19 each interconnected with the bore 21 in the shaft 9 or a single bag as desired. By the term mechanical pressure, is meant a pressure other than that produced on the fabric by centrifugal action.

The central bore 21 in the shaft 9 extends the entire length of the shaft and communicates at

the lower end thereof with a fluid pressure supply pipe 22 connected to the lower end of the shaft 9 by a swivel joint 23 whereby fluid pressure may be delivered to the bag 19 through the central bore 21 to inflate the bag. Such fluid pressure supply pipe 22 is connected to a supply pipe 24 under the control of a valve 25 that leads from a suitable source of supply such, for instance, as a compressed air tank. Pipe 22 is 5 also shown as being connected to a supply pipe 26 under control of a valve 27 that leads to a source of supply such as a compressor 28 mounted on the bottom 3 of the curb or casing 1 and having a driving pulley 29 connected to the pulley 10 13 by means of a belt 30 whereby the compressor 28 will be driven in unison with the basket 6 by the motor or power unit 5 to continuously and 15 increasingly supply fluid pressure to the bag 19 with rotation of the basket whereby pressure on the work increases as extraction progresses. Since the bag is flexible and fluid is supplied thereto increasingly as the extraction progresses, it will be seen that the bag will tend to follow the shape of the load which moves toward the 20 vertical walls of the basket due to centrifugal force. It will be understood that both sources of fluid pressure are seldom, if ever, employed at the same time and it will be seen that the compressor 28 is only effective when the apparatus 25 is in operation whereby the mechanical pressure applying means must be used in unison with the extraction operation when compressor 28 is employed, but when fluid pressure is supplied through pipe 24 the mechanical pressure for extraction may be applied before or after the basket is rotated. Therefore, the supply pipes 24 and 26 are provided with the valves 25 and 27. 30

In the operation of the apparatus, the hinged cover 2 is swung to open position, the bolts 18 40 are moved to unlocked position, and the cover 17 is lifted vertically by means of a lifting mechanism including hooks 31 adapted to engage perforated lugs 32 on the cover 17, the hooks 31 being raised and lowered by suitable power mechanism if desired. The height to which the cover 17 can be lifted is limited by the bag 19 attached to the cover 17 and to the shaft 9 but while in such lifted position liquid saturated or 45 filled fabric designated by the numeral 33 are placed in the perforated basket 6. Then, the cover 17 is lowered to the position shown, the bolts 18 are moved to a locked position and the hooks 31 detached from the lugs 32, the cover 2 is closed down, the basket 6 is rotated and fluid 50 pressure from a source of supply is admitted to the pipe 22. Such fluid pressure will pass through the bore 21 in the shaft 9 and into the bag 19 which will force the bag out to fill the space inside the basket 6 between the cover 17 and the saturated fabric 33. Continued admittance of fluid pressure to the bag 19 will cause a 55 mechanical pressure to be exerted on the fabric 33 to force any liquid out of the fabric by a squeezing action, the liquid draining off through the perforations in the basket 6 and through a drain pipe 34 at the bottom of the curb or casing 1. It will be apparent that since the bag 19 is wholly contained within the basket 6 and attached to parts thereof the motor or power unit 60 5 may be set in operation to cause rotation of the basket either before fluid pressure is supplied to the bag 19, during the time fluid pressure is being supplied to the bag 19, or after fluid pressure has been supplied thereto since the inflation of the bag 19 need not be affected by rotation of the 65 70 75

basket. Thus, a means has been provided for mechanically bringing about pressure other than centrifugal pressure on the contents of the extractor basket for squeezing such contents to remove liquid therefrom whereby the extracting force due to centrifugal action created by rotation of the basket will simply remove or expel the liquid clinging to the material and basket by capillary attraction. 80

With the above construction, a means is provided for removing liquid from fabric that embodies the use of both liquid expulsion through a squeezing action substantially in the same direction as the lines of fluid flow due to centrifugal action brought about by movement of two parts toward each other the fabric being disposed therebetween as well as a means for removing liquid from fabric by centrifugal action. The provision of such a mechanism insures that liquid clinging to the parts adjacent to and outside of the actual goods in the basket due to capillary attraction will be entirely removed by centrifugal force, this removal taking place with a substantially less speed of rotation of the basket than would otherwise be necessary should centrifugal action be employed alone. Thus, a means is provided for more effectively removing liquid from fabric with a less operating cost of the usual centrifugal apparatus, with less danger to an operator, and with less wear on apparatus parts. 90 95 100 105 Various other advantageous features will be apparent. 110

What I claim is:

1. Apparatus of the class described, comprising a casing, a rotatable material-receiving basket mounted within said casing and disposed around a central shaft extending upwardly within said casing, means for rotating said basket to subject material therein to centrifugal action for liquid removal, and means for subjecting the material to mechanical pressure as an aid to liquid removal by centrifugal action including a flexible bag secured to and having an inlet through said upstanding shaft, and means for passing fluid pressure through said inlet to inflate said flexible bag. 115 120 125

2. Apparatus of the class described, comprising a casing, a rotatable material-receiving basket mounted within said casing and disposed around a central shaft extending upwardly within said casing, means for rotating said basket to subject material therein to centrifugal action for liquid removal, and means for subjecting the material to mechanical pressure as an aid to liquid removal by centrifugal action including a flexible bag secured to and having an inlet through said upstanding shaft, and means for passing fluid pressure through said inlet to inflate said flexible bag by and simultaneously with rotation of said basket whereby the mechanical pressure on the material is constantly increased as the centrifugal action progresses. 130 135 140

3. Apparatus of the class described, comprising a casing, a rotatable material-receiving basket mounted within said casing and disposed around a central shaft extending upwardly within said casing, means for rotating said basket to subject material therein to centrifugal action for liquid removal, means for subjecting the material to mechanical pressure in directions substantially the same as the directions of flow of liquid under the centrifugal action as an aid to liquid removal by centrifugal action including a flexible bag secured to and having an inlet through said up- 145 150

- standing shaft, and means for passing fluid pressure through said inlet to inflate said flexible bag. 4. Apparatus of the class described, comprising a casing, a rotatable material-receiving basket mounted within said casing and disposed around a central shaft extending upwardly within said casing, means for rotating said basket to subject material therein to centrifugal action for liquid removal, means for subjecting the material to mechanical pressure in directions substantially the same as the directions of flow of liquid under the centrifugal action as an aid to liquid removal by centrifugal action including a flexible bag secured to and having an inlet through said upwardly standing shaft, and means for passing fluid pressure through said inlet to inflate said flexible bag by and simultaneously with rotation of said basket whereby the mechanical pressure on the material is constantly increased as the centrifugal action progresses. 5. In a machine of the class described, for extracting liquids from fabric articles, a perforate container for receiving the articles and having a rigid cover arranged to be removably secured in closed position on the container, a flexible bag secured with said cover to be disposed within said container when said cover is in closed position, and means for inflating said bag to cause its expansion against the work and including a fluid connection leading through the container wall, said connection being arranged to permit withdrawal of the bag with removal of the cover sufficiently to load and unload the container. 6. In a machine of the class described, for extracting liquids from fabric articles, a perforate container for receiving the articles and having a rigid cover arranged to be removably secured in closed position on the container, a flexible bag secured with said cover to be disposed within said container when said cover is in closed position, and means for inflating said bag to cause its expansion against the work and including a fluid connection leading through the container wall, said connection being located to permit withdrawal of the bag with removal of the cover sufficiently to load and unload the container. 7. In a machine of the class described, for extracting liquids from fabric articles, a perforate container for receiving the articles and having a rigid cover arranged to be removably secured in closed position on the container, a flexible bag secured with said cover to be disposed within said container when said cover is in closed position, and means for inflating said bag to cause its expansion against the work and including a fluid connection leading through the container wall opposite the cover, said bag being proportioned to permit sufficient removal of said cover without disconnection of the bag therefrom for convenient loading and unloading of said container. 8. In a machine of the class described, for extracting liquids from fabric articles, a generally cylindrical perforate container for receiving the articles and having an open end with a rigid cover therefor arranged to be removably secured in closed position on the container, a flexible bag secured centrally with said cover to be disposed within said container when said cover is in closed position, and means for inflating said bag to cause its expansion against the work and including a fluid connection leading centrally through the container wall opposite the cover to a position of communication with said bag adjacent the connection between said bag and said cover, said bag being of size to extend to the cylindrical wall of the container when the cover is in closed position. 9. In a machine of the class described, for extracting liquids from fabric articles, a rotatable perforate container for receiving the articles and having a rigid cover, means for removably securing the cover on the container, a flexible bag adapted to be disposed within said container to have bearing between the work and the cover, and means for inflating said bag to cause its expansion against the work during rotation of the container.
